UPTAKE CONSTRUCTION

Edward J. Mabrito, Richmond, Calif.

Application December 26, 1942, Serial No. 470,296

7 Claims. (Cl. 285—210)

The invention relates to the uptake or manifold structure such as used in conveying the products of combustion from the boilers of a ship to the smoke stack. Usually one uptake is utilized to a pair of boilers, and in the conventional type of uptake, there are three contiguous sections, to-wit: a pair of transversely spaced lower sections which are arranged for attachment to the boilers, a single upper section which is designed for attachment to stack, and a pair of intermediate sections which extend from the lower sections and lead into the upper section. All of the sections are substantially quadrangular in transverse cross-sections, the top section being square and having vertical sides, the bottom sections rectangular with long and narrow vertical sides, while the intermediate sections conform at one end with the lower sections, but converge and combine to conform at the other end with the upper section. The sections are formed of metal sheets arranged to be welded together at the edges so that the joints will be at the corners. The lower sections are required to be in appreciable offset relation to the front and sides of the upper section, and principally by reason of this fact, difficulty has previously been encountered in assembling and securing together the parts of the intermediate sections and securing same, to the other sections without buckling or setting up severe strains in the sheets comprising the sections. In previous constructions the sheets of the intermediate sections and the portions of the other sections to which such sheets were attached, were cut or formed in such manner that the corners of the sections changed from an obtuse angle at one end to an acute angle at the other. Usually the corners of the sections are supported by and seamed to angle iron bars, and in view of the variation in the angles, as aforesaid, the bars were bent to provide such an angle as will favor the corner joint nearest the lower section. Since it is not expedient to provide the angle iron bars with graduated angles or to wastefully trim the sheet stock for form fitting, it will be readily evident that the joints at the corners and between the sections will, for the most part, be ill-fitting and difficult to weld together. The edges will either overlap or present a crack which must be filled with weld metal, and the body of the sheets will be caused to buckle and incur stresses tending to rupture the joints, during expansion and contraction, of the parts in the use of the uptake.

In view of the above, it is an object of the present invention to provide an uptake construction in which the parts are so formed that they may

be economically produced, assembled and fitted together in a manner insuring effective jointure of the parts and sections and without requiring highly skilled labor.

5 Another object of the invention is to provide an uptake construction in which all of the sections, including the intermediate sections, will be in the form of true rectangles in transverse section, whereby the corners or joints may be supported by stock right-angle iron bars and all of the sheets constituting the walls of the sections may be laid and secured in position without any twisting or buckling.

The invention possesses other objects and features of advantage, some of which with the foregoing, will be set forth in the following description of the preferred form of the invention which is illustrated in the drawings forming and accompanying part of the specification. It is to be understood, however, that variations in the showing made by the said drawings and description may be adopted within the scope of the invention as set forth in the claims.

Referring to said drawings:

25 Figure 1 is an elevational view of the uptake as seen from the front.

Figure 2 is an elevational view of a side of the uptake.

Figure 3 is a view corresponding to Figure 1, but showing the uptake from the aft.

Figure 4 is a top plan view of the uptake as shown in Figure 1.

Figure 5 is a vertical sectional view of the uptake structure.

35 Figure 6 is a fragmentary view showing the same elevation as Figure 1, but of a slightly modified construction.

Figures 7 and 8 are perspective views of the uptake, looking from the front end rear thereof, the embodiment illustrated being that shown in Figures 1 to 5.

As illustrated in Figures 1 to 5, and 7 and 8, of the drawings, the uptake follows in general the typical arrangement wherein separate ducts 45 are provided for conveying the products of combustion from the combustion chambers of the boilers to a header which connects with the smoke stack. In such arrangement, the uptake is formed of what may be considered three sections, to-wit: a lower section 7 which is arranged for positioning immediately over the combustion chambers, an upper section 9 which is arranged to be positioned immediately under and operatively connected with the base of the smoke stack, and an intermediate section 8 interposed between

and connecting the upper and lower sections 7 and 9. Further, in accordance with the conventional practice, the sections are all made quadrangular in transverse section, the walls of the sections being formed of metal sheets joined at their side edges to form the corners of the sections. Both the upper and lower sections or boxes, as they are frequently termed, are made rectangular in cross-section, the upper section being square, while the lower sections are each formed with two of the sides considerably longer than the others. All sides of both sections 7 and 9 are vertical and with the corresponding sides parallel. The sections 7 are positioned at opposite sides of section 9 but in a lower plane, and in addition are offset rearwardly of the section 9 and with the longer transverse dimension of the sections 7 extending in the fore and aft direction of the uptake.

The cross-sectional area of section 9 is less than twice the corresponding areas of sections 7, and the intermediate sections 8 are made to conform with the bottom of the upper section 9. A division plate 10 is provided in the section 9 to keep the ducts separate. In changing from the lower to the upper form, the sections 8 are made to retain the width of the lower sections, but the fore and aft sides of the sections 8 are made to converge upwardly. These characteristic features of the typical uptake have made the problem of constructing the intermediate sections and the portions at the connection between such sections and the upper and lower sections, not easy of solution as evident by the several methods heretofore in use and characterized by the objections above explained.

In accordance with my invention, not only the upper and lower sections, but the intermediate sections are constructed so that the walls thereof define a rectangle in transverse section substantially throughout the entire length of the sections, thus making it possible for one thing to utilize standard angle iron bars for supporting the corners of the intermediate sections as well as the corners of the other sections. This utilization of the intermediate sections in the form stated obviously requires a type of jointure between, and a form of, the contiguous portions of the adjoining sections, entirely different from that employed in the old methods of connecting the sections. The change in the cross-sectional form of the intermediate sections and the change in the form of the contiguous portions of the different sections to be joined, constitutes a very important part of my invention.

Referring now more particularly to the construction of the uptake, as shown in the drawings, it will be seen that the intermediate sections 8 are provided with parallel sloping inner and outer side walls 16 and 17 respectively, arranged to extend upwardly and inwardly from the corresponding side walls 18 and 19 of the lower sections 7. Included also as part of the sections 8 are the front and rear side walls 21 and 22 which extend between the corresponding walls 23 and 24 of the bottom sections and 26 and 27 of the upper section. The walls 21 and 22 besides sloping inwardly and upwardly in conformity with the walls 16 and 17, as shown in Figure 1, and also upwardly and forwardly, as shown in Figure 2, converge toward one another as they extend from the lower to the upper section, as indicated in Figures 2 and 4.

The junctures of the outer side walls 17 and 19, and the inner side walls 16 and 18, are along

horizontal lines 28 and 29 respectively, as shown in Figures 2 and 5, the lines 28 being higher than the lines 29. Since the walls 16 and 17 of intermediate sections 8 are parallel, and the walls 21 and 22 thereof are in angular relation to the walls 23 and 24 of lower section 7, it will be evident that the juncture of these adjoining walls cannot be along straight lines intersecting the lines 28 and 29 unless, as is shown in the modified construction illustrated in Figure 6, one of the contiguous portions of adjacent walls is bent out of its normal plane and changed to that of the other wall. Where, as in the preferred embodiment, it is desired to avoid such bending and keep the walls 21 and 22 flat, the meeting edges or lines 31 and 32 between walls 21 and 23 and walls 22 and 24 are arranged, as shown in Figure 1, to be at an angle to lines intersecting lines 28 and 29. In view of the fact that the lower extremity of the side edges of the walls 16 are designed to meet the upper extremity of the side edges of wall 18, it will be seen that in order to provide for the desired meeting of the adjoining edges of the walls 21 and 23 and of the walls 22 and 24, the lines 31 and 32 will be at a greater angle to the horizontal than would the lines described as intersecting the junctures of the inner and outer side walls of the intermediate and lower sections. As the angular relation between walls 21 and 23 is thus made less than 180°, the portion 33 of the forward edge of walls 17 between the lines 28 and 31 is extended forwardly to meet the wall 23, and correspondingly the equivalent portion 34 of the rear edge of the walls 17 is cut or moved forwardly to meet the wall 24. It will thus be seen that while the side edges of the inner walls 16 continue in a straight line down to wall 18, the side edges of the wall 17 change to form angular parallel edge portions at the lower end thereof.

Both intermediate sections 8 are designed to lead into the bottom of section 9, and as will be clear from Figure 2, the outer walls 17 of sections 8 meet the corresponding walls 36 of section 9 in straight horizontal lines 37. Since the inner walls 16 are parallel to the outer walls 17, the former will likewise meet along a horizontal line 38 parallel to lines 37, the line 38 however, being at a lower level than line 37 by reason of the angular relation of the walls 16 and the distance between such walls and the walls 17. While the walls 16 and 17 thus join together or to the walls of section 9 along horizontal lines, the walls 21 and 22 in view of their right angular relationship to walls 16 and 17, can meet the plane of the front and rear walls of section 9 along a line inclined to the horizontal. In view of this and the fact that the walls 16 join at a lower level than the juncture of walls 17 and 36, the walls 26 and 27 are, as shown in Figures 1 and 3, provided with planar extensions 40 and 41 respectively, which depend sufficiently to reach the juncture of walls 16 and cover by means of tongues 42 the area between the lines 37 and the portion 43 of the side edges of walls 16 between such lines and said juncture. It will be understood that both the extensions 40 and 41, including the tongues 42, are coplanar with the respective walls 26 and 27 with which they are associated, and that except for the portions 43 the side edges of the walls 16 are retained straight throughout their length. In this manner a very simplified but effective construction for connection of such parts is afforded. As a modification of the structure just described, the

tongue portions 42 may be readily formed as integral parts of walls 21 and 22, as shown in Figure 6, instead of parts of the walls 36 of the upper section. Of course, in this modified arrangement, the tongue portions indicated in Figure 6 by the numerals 42 are bent out of the normal plane of the integrally associated walls, and made so as to conform with the plane of walls 26 when the walls 21 and 22 are in position. It will also be noted that in the embodiment illustrated in Figure 6, the portions 44 of the fore and aft sides of the uptake between the line 31' (located in position similar to line 31 or 32 of the first embodiment) and the line connecting the edges of lines 28 and 29, are also formed as integral parts of the walls 21 and 22 and bent so as to lie coplanar with the sides 23 and 24 when in position.

In most of the constructions of the type of uptake as involved herein, the wall structure is arranged to be reenforced by means of angle iron bars such as here indicated by the reference number 46. These bars, as before mentioned, are arranged to be positioned at the corners of the sections and in such manner that the two legs of each bar will lie against the adjoining walls and with the edges of such walls in close proximity so as to permit an effective welding operation. In view of the fact that my construction permits the use of conventional right-angle iron bars, the bars and walls may be firmly held together on initial assembly and readily tack-welded or otherwise secured, and at the same time since the edges of the adjoining walls may be readily held in desired close relation, the welding of the joints between the adjoining walls can be effectively accomplished in an economical manner.

As may be perceived, by comparing Figure 1 and 3, not only are the walls comprising the sides of the uptake of corresponding form, but the walls on the fore and aft sides of the uptake are for the most part identical in outline. This feature makes possible the manufacture of the parts at a relatively low cost, and in view of the many other economies afforded by the construction, hereinbefore pointed out, the uptake of my invention is not only much stronger than the constructions heretofore used, but a very appreciable reduction in cost is permitted.

I claim:

1. In an uptake construction, a pair of transversely-spaced lower sections and an upper section spaced vertically from and horizontally in advance of said lower sections, said sections being each rectangular in horizontal cross-section and having corresponding side and fore and aft walls vertical and parallel, a pair of intermediate sections interposed between and connecting each of said lower sections to the upper section and being rectangular in transverse section and with its walls joined to corresponding walls of the other sections, the walls of the intermediate sections, which extend in fore and aft direction of the uptake, having each of their forward and rear edges provided with angular related portions corresponding with the planes of the fore and aft sides of the upper and lower sections.

2. In an uptake construction, a pair of transversely-spaced lower sections and an upper section spaced vertically from and horizontally in advance of said lower sections, said sections each having its longitudinal axis extending vertically and each section being each rectangular in hori-

zontal cross-section and having corresponding side and fore and aft walls vertical and parallel, a pair of intermediate sections interposed between and connecting each of said lower sections

5 to the upper section and being rectangular in transverse section and with its walls joined to corresponding walls of the other sections, the contiguous fore and aft walls of adjoining sections being angularly related and the intersection of the fore and aft walls of adjoining sections defining a line of one side of a triangle in which one of the sides thereof intersects the junctures of the opposite side walls of adjoining sections and in which another of the sides is defined by the outer of the side walls of the intermediate section.

10 3. In an uptake construction, a pair of transversely-spaced lower sections and an upper section spaced vertically from and horizontally in advance of said lower sections, said sections being each rectangular in horizontal cross-section and having corresponding side and fore and aft walls vertical and parallel, a pair of intermediate sections interposed between and connecting each of said lower sections to the upper

20 section and being rectangular in transverse section and with its walls joined to corresponding walls of the other sections, the contiguous fore and aft walls of adjoining sections being angularly related and the intersection of the fore and aft walls of adjoining sections defining a line of one side of a triangle in which one of the sides thereof intersects the junctures of the opposite side walls of adjoining sections and in which another of the sides is defined by the outer of the side walls of the intermediate section.

25 4. In an uptake construction, a pair of transversely-spaced lower sections and an upper section positioned meditately and forwardly of and above the lower sections and having a corresponding axis, the lower sections being correspondingly positioned and rectangular in horizontal cross-section and having adjacent fore and aft walls shorter than the side

30 walls, the upper section being rectangular in cross-section with its fore and aft walls wider than and parallel to the corresponding walls of the lower sections and with its side walls narrower than the side walls of the lower sections,

35 5. In an uptake construction, a pair of transversely-spaced lower sections and an upper section positioned meditately and forwardly of and above the lower sections and having a corresponding axis, the lower sections being correspondingly positioned and rectangular in horizontal cross-section and having adjacent fore and aft walls shorter than the side

40 walls, the upper section being rectangular in cross-section with its fore and aft walls wider than and parallel to the corresponding walls of the lower sections and with its side walls narrower than the side walls of the lower sections,

45 6. In an uptake construction, a pair of transversely-spaced lower sections and an upper section positioned meditately and forwardly of and above the lower sections and having a corresponding axis, the lower sections being correspondingly positioned and rectangular in horizontal cross-section and having adjacent fore and aft walls shorter than the side

50 walls, the upper section being rectangular in cross-section with its fore and aft walls wider than and parallel to the corresponding walls of the lower sections and with its side walls narrower than the side walls of the lower sections,

55 7. In an uptake construction, a pair of transversely-spaced lower sections and an upper section positioned meditately and forwardly of and above the lower sections and having a corresponding axis, the lower sections being correspondingly positioned and rectangular in horizontal cross-section and having adjacent fore and aft walls shorter than the side

60 walls, the upper section being rectangular in cross-section with its fore and aft walls wider than and parallel to the corresponding walls of the lower sections and with its side walls narrower than the side walls of the lower sections,

65 8. In an uptake construction, a pair of transversely-spaced lower sections and an upper section positioned meditately and forwardly of and above the lower sections and having a corresponding axis, the lower sections being correspondingly positioned and rectangular in horizontal cross-section and having adjacent fore and aft walls shorter than the side

70 walls, the upper section being rectangular in cross-section with its fore and aft walls wider than and parallel to the corresponding walls of the lower sections and with its side walls narrower than the side walls of the lower sections,

75 9. In an uptake construction, a pair of transversely-spaced lower sections and an upper section positioned meditately and forwardly of and above the lower sections, the lower sections being correspondingly positioned and rectangular in horizontal cross-section and having fore and aft

walls shorter than the side walls, the upper section being rectangular in cross-section with the fore and aft walls wider than and parallel to the corresponding walls of the lower sections and with its side walls narrower than the side walls of the lower sections, each of said sections having its longitudinal axes extending vertically, a pair of intermediate sections interposed between and connecting said upper to each of said lower sections, and being rectangular in transverse cross-section and with its walls joined to the corresponding walls of the other sections, the outer side walls of the intermediate sections meeting the corresponding walls of the other sections along parallel horizontal lines and the inner side walls of the intermediate sections substantially meeting at the top and joining with the corresponding walls of the lower sections along horizontal parallel lines, the side walls of the intermediate sections having their forward and rear edges provided with angular related portions corresponding with the planes of the fore and aft sides of the adjoining sections, the contiguous fore and aft walls of adjoining sections being angularly related and the intersection of the fore and aft walls of adjoining sections defining a line of one side of a triangle in which one of the sides thereof intersects the junctures of the opposite side walls of adjoining sections and in which another of the sides is defined by one of said angular related portions.

6. In an uptake construction, a pair of transversely-spaced lower sections and an upper section positioned meditately and forwardly of and above the lower sections, the lower sections being correspondingly positioned and rectangular in horizontal cross-section and having fore and aft walls shorter than the side walls, the upper section being rectangular in cross-section with the fore and aft walls wider than and parallel to the corresponding walls of the lower sections and with its side walls narrower than the side walls of the lower sections, a pair of intermediate sections interposed between and connecting said

upper to each of said lower sections, and being rectangular in transverse cross-section and with its walls joined to the corresponding walls of the other sections, the outer side walls of the intermediate sections meeting the corresponding walls of the other sections along parallel horizontal lines and the inner side walls of the intermediate sections substantially meeting at the top and joining with the corresponding walls of the lower sections along horizontal parallel lines, the fore and aft walls of each of the upper and lower sections having extensions with angular related edges at least one which is at the juncture with the intermediate sections.

7. In an uptake construction, a pair of transversely-spaced lower sections and an upper section positioned meditately and forwardly of and above the lower sections, the lower sections being correspondingly positioned and rectangular in horizontal cross-section and having fore and aft walls shorter than the side walls, the upper section being rectangular in cross-section with the fore and aft walls wider than and parallel to the corresponding walls of the lower sections and with its side walls narrower than the side walls of the lower sections, a pair of intermediate sections interposed between and connecting said upper to each of said lower sections, and being rectangular in transverse cross-section and with its walls joined to the corresponding walls of the other sections, the outer side walls of the intermediate sections meeting the corresponding walls of the other sections along parallel horizontal lines and the inner side walls of the intermediate sections substantially meeting at the top and joining with the corresponding walls of the lower sections along horizontal parallel lines, the fore and aft walls of the intermediate sections having at least at one of the ends thereof a triangular-shaped integral extension bent out of the normal plane of the wall and conforming to the plane of the wall of the adjoining section.

EDWARD J. MABRITO.
